UNITED STATES PATENT OFFICE.

EDWARD GREENWOOD, OF PHILLIPS, MAINE.

TOOTHPICK-MACHINE.

1,376,616.

Specification of Letters Patent.

Patented May 3, 1921.

Application filed April 10, 1920. Serial No. 372,819.

To all whom it may concern:

Be it known that I, EDWARD GREENWOOD, a citizen of the United States, residing at Phillips, in the county of Franklin and 5 State of Maine, have invented certain new and useful Improvements in Toothpick-Machines, of which the following is a specification.

My invention relates to machines for cutting splints from veneer strips and more particularly to toothpick machines.

These machines consist essentially of a stationary knife secured to the body of the machine with its edge upward and across 15 the upper edge of the knife is fed the veneer strip by means of a continuously acting set of feed rolls.

The veneer strip is forced against the upper edge of the knife by means of a wood 20 cutting block secured to the lower end of an eccentric rod operated by an eccentric secured to the main shaft of the machine.

The machines run with great rapidity at the rate of 3,000 revolutions a minute and 25 the splints or toothpicks are chopped off successively from the end of the strip as the veneer strip feeds over the knife.

The vertical reciprocating motion of the cutting knife is guided by vertical guides 30 or grooves which engage the slides of the cross head to which the cutting block is attached.

This sliding contact between the cross head and the vertical guide causes an excessive vibration and the wear of the machine soon produces a loose fit which is the cause of much vibration and jar while the machine is running at a high rate of speed.

For the purpose of lifting the veneer 40 strip after it has been forced down into the knife to cut the splint or toothpick, a spring plate is used which plate acts to support the strip as it approaches the knife.

The cutting block as it depresses the veneer 45 strip also depresses the spring plate underneath and when it rises the spring plate lifts the veneer to a position slightly above the edge of the knife where it can feed forward for the next cut.

50 The quick and heavy blow thus struck the spring plate when the cutting block descends causes a corresponding upward action as the spring flies back upon being released by the cutting block.

55 As the spring plate is perfectly free at its forward point to spring upward carry-

ing with it the veneer strip the latter is thrown higher than necessary thus interfering with the accurate cutting of the knife and the spring plate is also liable to break 60 by its rapid upward rebound.

The object of my invention is to avoid a sliding contact between the cross head and its guides and to substitute therefor means for holding more firmly and steadily in 65 place the lower end of the eccentric rod and the cutter block.

A further object of my invention is to improve the construction of the spring plate to avoid the liability of breakage and 70 to secure more accurate cutting of the splint or toothpick.

According to my invention I substitute for the vertical guide and sliding cross head a pair of links connected at one end 75 with the lower end of the eccentric rod and at the other end with a permanent portion of the machine.

These links extend out in substantially a horizontal position and the only wearing 80 motion is at the pivoting or connecting points and consists simply of a slight rotation in the pivotal bearings.

The cutting block and the holder to which it is attached are thus firmly held without 85 any lateral vibration and the result is that the machine may be run with a greatly increased speed and greatly diminished vibration.

The vertical motion of the cutting block 90 is only about $\frac{1}{4}$ of an inch and where there is substantially no lateral vibration it may be run as high as 6,000 revolutions a minute with no perceptible jar or rattle.

I remedy the difficulty with the spring 95 plate spoken of by forming on one of its edges a lateral projection which extends into a recess in the lateral strip guide, the recess being so arranged as to limit the inward motion of the strip and prevent its 100 rising too high on its reaction from the blow of the cutting block.

I have illustrated my invention by means of the accompanying drawing in which I have shown so much of the toothpick machine as is necessary to show the operation 105 of my device with my improved guiding mechanism attached.

Referring to the drawing:

Figure 1 is a front elevation taken from 110 the side where the veneer strip enters the machine.

Fig. 2 is a section on the line 1—1 of Fig. 1, Fig. 3 is a section on the line 2—2 of Fig. 4, and

Fig. 4 is a plan view of the spring lifting plate and the lateral guide.

In the drawing 1 represents the main shaft, 2—2 its journal bearings formed on the upper ends of the standard 3—3.

The shaft has secured to it the eccentric 10 4 having an eccentric strap 5 and an eccentric rod 6. These parts are all common in the old forms of toothpick machines except that the eccentric or eccentric straps have a relatively long bearing on the shaft and the 15 eccentric rod is made in two parts separated by considerable distance so that they are held firmly and are free from any lateral vibrations. Connected with the lower ends of the eccentric rod 6, as here shown, formed 20 integral therewith, is a holder 7 to which is bolted the cutting block 8.

The holder and the cutting block are guided and held in position by a pair of links 9—9 pivoted to the cutting block holder 25 by a shaft or pin 10.

Each of the links 9 extends forward in a substantially horizontal position and the front end is offset downward and pivoted to the bed of the machine by a pin or shaft 11.

30 The links 9—9 are cut away by numerous openings to reduce their weight as much as possible and thus facilitate the rapid movement of the cutting block in its holder.

The veneer strip 14 is fed through the 35 machine over the spring plate 13 between the rolls 12 and over the knife 15 secured in a suitable manner to the base of the machine.

At opposite edges of the spring plate are 40 two projections 16, one on each edge. The projection 16 fits into a recess 17 formed in the lateral guide 18, the function of which is to guide the veneer strip laterally as it passes through the machine.

45 It will be readily understood that the upward movement of the spring plate is checked by the projection 16 coming in contact with the upper portion of the recess 17 when the plate springs too far or far enough to cause liability of breakage.

50 It will be seen that a toothpick machine or other machine having a rapidly vibrating cutting block or similar part may be run much more rapidly by the use of my guiding links than by vertically sliding guides.

55 The link connection as indicated is preferably pivoted as shown but if made long enough and flexible enough it may be fastened rigidly at both ends as the extent of

motion is very slight and the material of the 60 links might easily spring to that extent without exceeding its limit of elasticity.

While I have specified that the device is intended for use in connection with the cutting block it is to be understood that in the 65 term "cutting block" I desire to include a reciprocating knife or any like instrumentality where rapid vertical reciprocation with little lateral vibration is desirable, the ends in such constructions being pivoted to 70 all intents and purposes.

I claim:

1. In a machine for cutting toothpicks, the combination of a shaft, an eccentric and eccentric rod thereon, a cutting block carried 75 by said eccentric rod, a guide link for holding said cutting block in position, a stationary knife coacting with said cutting block and means for feeding a veneer strip over said knife.

2. In a machine for cutting toothpicks the combination of a shaft, an eccentric and eccentric rod thereon, a cutting block carried by said eccentric rod, a guide link pivoted by one end to the eccentric rod and by the 85 other end to the machine for holding said cutting block in position, a stationary knife coacting with said cutting block and means for feeding a veneer strip over said knife.

3. In a machine for cutting toothpicks, the 90 combination of a shaft, an eccentric and eccentric rod thereon, a cutting block holder at the end of said eccentric rod, a cutting block secured to said holder, guide links pivoted by one end to said cutting block holder 95 and by the opposite end to the machine, a stationary knife coacting with said cutting block and means for feeding a veneer strip over said knife.

4. In a machine of the character described, 100 the combination of a spring plate for lifting the veneer strip, having a lateral projection and a lateral guide adjacent to said spring plate and outside the main edge of the same having a recess to receive said projection 105 and arranged to limit its upward motion.

5. In a machine of the character described, the combination of a spring plate for lifting the veneer strip, having a lateral projection and a lateral guide adjacent to said 110 spring plate and outside the main edge of the same having a recess with a shoulder above said projection to limit the upward movement of said spring plate.

In testimony whereof I have affixed my 115 signature.

EDWARD GREENWOOD.
